SERVING TRAY

Louis H. Barnett and Harris Brin,
Fort Worth, Tex.

Application September 6, 1952, Serial No. 21,372

Term of patent 14 years

(Cl. D44—10)

To all whom it may concern:

Be it known that we, Louis H. Barnett and Harris Brin, both citizens of the United States and both residing at Fort Worth, Texas, county of Tarrant, and the State of Texas, have invented a new, original, and ornamental Design for a Serving Tray, of which the following is a specification, reference being had to the accompanying drawing, forming part thereof.

Figure 1 is a perspective view of a serving tray showing our new design, and illustrating the same in its closed position.

Figures 3 and 4 are end and side elevations, respectively, of the serving tray, both showing their closed positions.

We claim:

The ornamental design for a serving tray, substantially as shown.

LOUIS H. BARNETT.
HARRIS BRIN.
